United States Patent Office.

WYATT W. MILLER, OF SAFE HARBOR, PENNSYLVANIA.

Letters Patent No. 70,011, dated October 22, 1867.

IMPROVEMENT IN THE CONSTRUCTION OF FAGOT FOR BEAM.

The Schedule referred to in these Letters Patent and making part of the same.

TO ALL WHOM IT MAY CONCERN:

Be it known that I, WYATT W. MILLER, of Safe Harbor, in the county of Lancaster, and State of Pennsylvania, have invented a new and improved Fagot for Beams; and I do hereby declare that the following is a full, clear, and exact description thereof, which will enable others skilled in the art to make and use the same, reference being had to the accompanying drawings, forming part of this specification.

Figure 1 represents a side elevation of my invention.

Figure 2 is an end elevation, showing the method of confecting the plates, and

Figure 3 an end elevation of a modification of my invention.

Similar letters of reference indicate corresponding parts in the drawing.

This invention relates to a new manner of forming piles for fagot for large double-flange beams for building bridges and other structures, and it consists in composing the whole fagot of flat plates, and connecting them together by means of bars dove-tailed into the ends of such plates, so that the fagot, when thus made, will represent, as nearly as possible, the shape of the finished beam.

In the drawings, A A are bars rolled into the required width and thickness, and provided, at their ends, with transverse dove-tailed grooves, at regular distances apart, and cut into the required length. These plates form the top and bottom of the pile or fagot. The web is composed of upright or horizontal plates B B, which are interposed between the plates A A, as shown in the drawings. The whole is then united by suitable bars C C, which are let into dove-tailed slots in the top and bottom plates or flanges, and in the web flush with the ends of the pile. In fig. 3 the bars C are dove-tailed into the flanges upon the outer sides of the web formed of vertical plates, by which means such web is held in position. Instead of having but one plate A on the top and bottom, two or more can be employed, as is shown in fig. 3.

A fagot thus made can be easily handled when piled preparatory to being heated for rolling into the required shape.

Having thus described my invention, what I claim as new therein, and desire to secure by Letters Patent, is—

The fagots for piling beams of smooth top and bottom plates A A, vertical or horizontal plates forming the web B, all secured together by the bars C, dove-tailed into such top and bottom plates flush with their ends, and into the web B or upon its outer sides, substantially as herein shown and described.

The above specification of my invention signed by me this 11th day of July, 1867.

WYATT W. MILLER.
